UNITED STATES PATENT OFFICE

LESLIE A. HOPKINS, OF DETROIT, MICHIGAN

ELECTRIC HEATER

Application filed November 10, 1930, Serial No. 494,490. Renewed October 26, 1931.

This invention relates to heaters.

An object of this invention is a heater employing electrical current as a fuel.

A further object is a heater having a completely sealed, heated air conduit in which is disposed a fan for causing circulation of the air, a heating unit, which may be made up of electrical heat coils or the like, disposed in the outlet path of said fan and radiators thru which flow the heated air rising from the electrical heating units.

The heater described in the foregoing may be "charged" with a supply of heated air, the charge being created by permitting the coils to operate during the off hours when the cost of electrical supply is at its lowest. The heated air is retained in its casing by an insulating jacket and only when an outside agency such as a second fan is turned on, will great quantities of heat be dissipated from the radiators. The normal heat loss from the heater is very small, due to the insulation provided.

Heaters of the class described in the foregoing have been found extremely economical and efficient for use wherever an instantaneous supply of heated air is desired, such as, for example, in gas filling stations, outbuildings, etc.

Still other objects will readily occur to those skilled in the art upon reference to the following description and the accompanying drawings in which

Fig. 1 is a front elevation view of the heater.

Fig. 2 is a side view of the same.

Fig. 3 is a view of the device.

Fig. 4 is a section as if on the line 4—4 of Fig. 3.

Referring to the drawings there is shown a casing 10 having near its lower portion a shelf 12 under which may be disposed a fan casing 14 of any well known type. Disposed within the casing 14 is a fan, not shown, operable by means of a motor 16 supported on the standard 18, access to the motor being had by the door 20 to which is hinged at 22 and is provided with a suitable latching means 24.

Connected to the outlet of the fan is a duct 30 leading into a chamber 34 in which

are disposed electrical heating coils 36. The supply of electrical current for the coils 36 is brought in thru a conduit 37, thru which projects a cable 40, the latter being hermetically sealed in the conduit and having on its end an electrical plug fitting 42 of the well known type.

From the upper end of the chamber 34, a second duct like portion 38 projects thru the top of the casing 10 and connected to the upper end of the portion 38 are a plurality of radiators 40 which form connections between the upper end of the duct 38 and the upper end of a pipe 44 whose lower end discharges into the fan inlet at 46.

The radiators 40 are each provided with a plurality of heat radiating fins 48 and it will be observed that air coming from the pipe 44 thru the inlet 46 will be forced upwardly by the fan thru duct 30, into contact with the heating units 36 where it will be heated, and out thru the duct 38 into the radiators 40, giving up its heat to the fins 48 after which it escapes back into the pipe 44 to resume its travel once more.

Disposed behind the radiators 40 is a second fan 52 operable by means of a motor 54 mounted upon a standard 56, the fan 52 being rotated only when a supply of heated air is desired. The fan 52 draws cold air from the rear of the heater and blows it past the radiating fins 48, where it absorbs the heat therefrom, and becomes heated, the air then passing out in front of the heater.

In this manner instantaneous supply of heated air is obtained, as will be readily observed.

The radiators 40 may be mounted in an auxiliary casing 58 and the portions of the duct and pipe which project thru the main casing 10 may be covered by suitable insulation, such as is shown at 60.

Further, the casing 10 is also filled with insulation, such as mineral wool, or the like, which serves to reduce the heat loss.

It will be observed that there has been provided an efficient heater which can be charged during the hours when the cost of charging is at its lowest, the charging being accomplished by virtue of the fact that the air

maintained in the system cannot escape, the system being sealed. The air becomes heated or "charged" and may be utilized as a heating medium whenever desired, and in a simple manner, merely by rotating the fan 52.

Now having described the invention and the preferred embodiment thereof, it is to be understood that the said invention is to be limited, not to the specific details herein set forth, but only by the scope of the claims which follow.

What I claim is:

1. In a heater including an insulating casing, a fan casing, an air duct, whose lower end is connected to the fan casing outlet, electrical heating units in said duct between its ends, a pipe having its lower end connected to the fan casing inlet, connections between the upper ends of the duct and pipe, and a fan in said casing serving to draw air down thru said pipe and force it upwardly thru said duct, said connections being exposed to the medium to be heated by said heater and being provided with exteriorly projecting heat radiating fins which serve to radiate to the medium the heat imparted to the air in said duct by said electrical heating units.

2. In a heater including an insulating casing, a fan casing, an air duct, whose lower end is connected to the fan casing outlet, electrical heating units in said duct between its ends, a pipe having its lower end connected to the fan casing inlet, connections between the upper ends of the duct and pipe, and a fan in said casing serving to draw air down thru said pipe and force it upwardly thru said duct, said connections being provided with heat radiating fins, which serve to radiate the heat imparted to the air in said duct by said electrical heating units.

3. In a heater including an insulating casing, a fan casing, an air duct whose lower end is connected to the fan casing outlet, electrical heating units in said duct between its ends, a pipe having its lower end connected to the fan casing inlet, connections between the upper ends of the duct and pipe, and a fan in said casing serving to draw air down thru said pipe and force it upwardly thru said duct, said connections being provided with heat radiating fins, which serve to radiate the heat imparted to the air in said duct by said electrical heating units, there being a fan disposed behind said connections and serving to force cold air, which is to be heated, into intimate contact with said fins and then into the space in front of said heater, the fan casing, the duct, the connections, and the pipe forming a completely and hermetically sealed, air heating conduit.

4. In a heater including an insulating casing, a fan casing, an air duct, whose lower end is connected to the fan casing outlet, electrical heating units in said duct between its ends, a pipe having its lower end connected to the fan casing inlet, connections between the upper ends of the duct and pipe, and a

fan in said casing serving to draw air thru said pipe and force it upwardly thru said duct, the fan casing, the duct, the connections, and the pipe forming a completely and hermetically sealed, air heating conduit, said connections being exposed to the medium to be heated by said heater and being provided with exteriorly projecting heat radiating fins which serve to radiate to the medium the heat imparted to the air in said duct by said electrical heating units.

5. In a heater including an insulating casing, a fan casing, an air duct, whose lower end is connected to the fan casing outlet, electrical heating units in said duct between its ends, a pipe having its lower end connected to the fan casing inlet, connections between the upper ends of the duct and pipe, and a fan in said casing serving to draw air down thru said pipe and force it upwardly thru said duct, said connections being provided with heat radiating fins, which serve to radiate the heat imparted to the air in said duct by said electrical heating units, the fan casing, the duct, the connections, and the pipe forming a completely and hermetically sealed, air heating conduit.

6. In a heater including an insulating casing, a fan casing, an air duct whose lower end is connected to the fan casing outlet, electrical heating units in said duct between its ends, a pipe having its lower end connected to the fan casing inlet, connections between the upper ends of the duct and pipe, and a fan in said casing serving to draw air down thru said pipe and force it upwardly thru said duct, said connections being provided with heat radiating fins, which serve to radiate the heat imparted to the air in said duct by said electrical heating units, there being a fan disposed behind said connections and serving to force cold air, which is to be heated, into intimate contact with said fins and then into the space in front of said heater, the fan casing, the duct, the connections, and the pipe forming a completely and hermetically sealed, air heating conduit.

7. In a heater including an insulating casing, a fan casing, an air duct whose lower end is connected to the fan casing outlet, electrical heating units in said duct between its ends, a pipe having its lower end connected to the fan casing inlet, connections between the upper ends of the duct and pipe, and a fan in said casing serving to draw air down thru said pipe and force it upwardly thru said duct, said connections being exposed to the medium to be heated by said heater and being provided with exteriorly projecting heat radiating fins which serve to radiate to the medium the heat imparted to the air in said duct by said electrical heating units, there being means to cause a flow of the medium by and around the fins.

8. In a heater including an insulating cas-

- ing, a fan casing, an air duct, whose lower end is connected to the fan casing outlet, electrical heating units in said duct between its ends, a pipe having its lower end connected to the fan casing inlet, connections between the upper ends of the duct and pipe, and a fan in said casing serving to draw air thru said pipe and force it upwardly thru said duct, the fan casing, the duct, the connections, and the pipe forming a completely and hermetically sealed, air heating conduit, said connections being exposed to the medium to be heated by said heater and being provided with exteriorly projecting heat radiating fins which serve to radiate to the medium the heat imparted to the air in said duct by said electrical heating units, there being means to cause a flow of the medium by and around the fins.
- 20 9. In a heater, a vertical casing having therein heat insulating material, a pair of ducts passing vertically upward through the casing and insulating material, one of said ducts being larger than the other, means providing communication between the ducts at the lower ends thereof and including an air circulating device delivering into the larger, means providing communication between the ducts at the upper ends thereof and including
- 25 30 a heat radiating device, and heating means disposed in the larger duct for heating gaseous fluid circulating therethrough.
10. In a heater, a vertical casing having therein heat insulating material, a pair of ducts passing vertically upward through the casing and insulating material, one of said ducts being larger than the other and including a relatively large chamber, means providing communication between the ducts at
- 35 40 the lower ends thereof and including an air circulating device delivering into the larger, means providing communication between the ducts at the upper ends thereof and including a heat radiating device, and heating means
- 45 disposed in the larger duct in said chamber for heating gaseous fluid circulating therethrough.

LESLIE A. HOPKINS.
